THREAD GRINDING MACHINE

Gilbert Stewart and Guenther Brinkmann, Detroit, and Harold N. Seyerth, East Detroit, Mich., assignors to Ex-Cell-O Corporation, Detroit, Mich., a corporation of Michigan

Application July 17, 1943, Serial No. 495,162

15 Claims. (Cl. 51—95)

1

The present invention relates to machine tools, and has particular reference to thread grinding machines.

One of the objects of the invention is to provide a novel thread grinding machine which may be operated with an automatic cycle, and which embodies a simplified and comparatively inexpensive structure for effecting wheel feed, dresser feed, wheel retraction and advance, and taper adjustment.

A more specific object is to provide a new and improved thread grinding machine in which all movements of the grinding wheel are effected through a single wheel slide, and in which wheel retraction and advance and taper adjustment are imparted through an actuating linkage to the wheel slide without altering the infeed adjustment.

Another object is to provide a novel thread grinding machine having a combined hydraulic and mechanical drive for rotating and translating the work spindle in timed relation, and in which the drive is subject to selective speed variation at different points in the machine cycle, for example, to vary the speed selectively for a series of rough grinding passes over the thread proper, one finish grinding pass over the thread proper, removal of the incomplete end thread convolution at the end of each grinding pass, and the free return strokes between successive grinding passes.

A further object is to provide a new and improved thread grinding machine of the foregoing character in which the grinding wheel is rotated at different speeds in timed relation to the variations in speed of the work spindle for rough grinding, finish grinding and dressing.

Other objects and advantages will become apparent as the description proceeds.

In the accompanying drawings.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the 35 spirit and scope of the invention as expressed in the appended claims.

Referring more particularly to the drawings, the machine constituting the exemplary embodiment of the invention is adapted for grinding 45 screw threads on various types and forms of workpieces, and in the present instance a work blank W of an aircraft engine cylinder barrel is shown.

The machine comprises an elongated horizontally disposed main base 1 formed on the top

with a longitudinal set of ways 2 for supporting a reciprocating work table 3, and having a rearward extension 4 formed with a set of transverse ways 5 for supporting a tool head 6. A rotary tool spindle 7 is mounted in the tool head 6 for rotation on an axis extending generally longitudinally of the table 3, and supports a suitable grinding wheel G.

A headstock or work head 8, and a suitable tailstock 9, are mounted in longitudinally spaced relation on the table 3 for reciprocation therewith. Journalized in the headstock 8 is a work spindle 10 having a chuck 11 in which one end of the work blank W is secured for rotary drive. The other end of the blank is rotatably supported by the tailstock 9. A combined hydraulic and mechanical drive transmission is provided for translating the table 3 and rotating the work spindle 10 in timed relation and in forward and reverse directions at different selective speeds. Thus, the work blank W is adapted for rotation and translation axially through cutting engagement with the grinding wheel G in timed relation to the rotation as determined by the lead of the thread or threads to be ground.

The tool head 6 is shiftable transversely of the work spindle 10 either forwardly to locate the grinding wheel G in operative grinding position, or rearwardly to locate the wheel in idle or retracted position. A cross feed mechanism 12 is provided for automatically adjusting the operative grinding position of the wheel G step-by-step in timed relation to the successive working passes of the work spindle 10 until the blank W has been ground to final size. The shifting of the tool head 6 is effected by a retract mechanism 13 which is automatically operable to separate the grinding wheel G laterally from the blank W for each rapid traverse return movement of the table 3 without changing the setting of the cross feed mechanism. A taper mechanism 14 is optionally available for automatically superimposing a taper adjustment on the infeed position of the grinding wheel G in timed relation to the longitudinal traverse of the table 3 as determined by the form or degree of taper desired on the work.

Mounted on the tool head 6 at the rear of the grinding wheel G is a suitable dressing mechanism 15 for dressing or truing the grinding surface. The dressing mechanism 15 is automatically operable at selected times in the machine cycle, and in each operation serves to effect a dresser feed of the dressing tool or tools toward the grinding wheel, and simultaneously a compensating feed of the tool head 6 toward the axis of the work spindle 10 so as to compensate for the reduction in diameter of the grinding wheel G.

The operation of the machine is controlled by a combined hydraulic and electric system in which the movements of the main units are interlocked and timed, and which is selectively adjustable to obtain different automatic machine cycles. In one illustrative cycle, adapted for grinding the threads on aircraft engine cylinder barrels, the work table 3 is reciprocated a predetermined number of times, each reciprocation consisting of a forward grinding pass at a relatively slow speed and a return stroke at a rapid traverse speed. For example, there may be five roughing passes at a fast grinding speed and a final or finishing pass at a slow grinding speed. At the end of each roughing and finishing pass, the grinding speed is reduced during

the final work spindle revolution or preselected portion thereof if the incomplete thread convolution on the leading end of the work blank is to be removed. The spindle 10 is always rotated in timed relation to the table traverse, and is reversed upon each reversal of the table. At the start of the cycle and also preceding each grinding pass, the grinding wheel G is advanced into operative grinding position, and then advanced additionally in a feed adjustment through a predetermined increment toward the work axis except before the first pass. At the end of each grinding pass, the grinding wheel G is retracted into the idle or dressing position without interfering with the cumulative infeed adjustment. The grinding wheel may be dressed upon movement into retracted position after any desired number of grinding passes, for example after the first and third roughing passes, and again after the fifth roughing pass before the final or finishing pass. In each dressing operation, the dressing cycle is initiated at the start of the retract movement of the tool head 6, and continues during the following free return movement of the work head 8, and if necessary the table 3 will dwell at the end of the return movement to permit completion of the cycle. The dressing cycle comprises a feed of the dressing mechanism 15 toward the grinding wheel G, a compensating feed of the wheel G toward the work axis, and truing of the grinding surface to the depth of the dresser feed. During the dressing operation, the grinding wheel G preferably is driven at a reduced speed.

The work head

The work head 8 per se forms no part of the present invention, and therefore is not described in full detail. The mechanical drive transmission within the work head 8 for the table 3 and spindle 10 is generally similar to that shown in a copending application for United States Letters Patent by Guenther Brinkmann, Serial No. 435,224, filed March 18, 1942 (now Patent No. 2,389,590, issued November 27, 1945), and comprises a screw shaft 16 geared to the spindle 10, and connected through a meshing worm 17 and worm wheel 18 to an inlet shaft 19 extending to the rear of the head 8 for connection to a suitable source of power. The wheel 18 is slidably splined to the shaft 16 so as to permit relative axial movement of the latter, and is itself constrained against axial movement by bearing lugs 18a at opposite sides rigidly supported within the head. A lead screw 20 on the shaft 16 engages a nut 21 fixed in relation to the machine base 1 to complete the drive for the table traverse. Upon rotation of the power inlet shaft 19, the work spindle 10 and the lead screw 20 are driven in positively timed relation to rotate and translate the workpiece W in accordance with the thread lead to be ground thereon in forward and reverse directions.

A lead pick-up mechanism, operable by means of a hand wheel 22 at the front of the machine, is provided for adjusting the position of translation of the table 3 relative to the position of rotation of the work spindle 10, as required to locate the work thread in proper position for engagement by the grinding wheel G.

Backlash compensating means likewise is provided for automatically adjusting the position of translation of the table 3 relative to the position of rotation of the spindle 10 in one direction or the other to the extent of the backlash in the

drive upon each reversal of the lead screw 20, so as to maintain the work thread in proper relation to the grinding wheel G in both directions of table translation. In the present instance, the backlash compensating means comprises a hydraulic actuator 23 (Fig. 14) which is reversible upon each reversal of the work table 3 to adjust the drive connection through a predetermined adjustable distance required to compensate for backlash. The actuator 23 comprises a piston 24 reciprocable in a cylinder 25 having fluid supply lines 26 and 27 opening to opposite ends and connected to a control valve 28 forming part of the main valve panel 29. The valve 28 is of the two-position type, and is adapted for operation by two solenoids SVCR and SVCL in the electric control circuits for the machine. During the forward drive to the right, the solenoid SVCR is energized to actuate the valve 28 into one end position in which the cylinder lines 26 and 27 are connected respectively to fluid pressure and exhaust lines 30 and 31 to take up the backlash in the proper direction. During the return drive to the left, the solenoid SVCR is deenergized, and the solenoid SVCL is energized to actuate the valve 28 into the other position, thereby reversing the connections to the cylinder lines 26 and 27 so as to take up the backlash in the opposite direction.

The work head drive

The drive for the work head 8 is automatically adjustable to vary the speed of spindle translation and rotation in accordance with the nature of the work being done at different points in the machine cycle, and comprises a reversible hydraulic motor 32 of the rotary type having a constant displacement at any given speed. A pulley 33 on the shaft 34 of the motor 32 is connected through a belt 35 to a pulley 36 on the rear outer end of the power inlet shaft 19 of the tool head 8 (Fig. 2).

The motor 32 has fluid supply lines 37 and 38 connected in a hydraulic transmission system (Fig. 13) to receive fluid under pressure, subject to control by a direction valve 39 and an orifice selection valve 40, from the pressure line 41 of a variable delivery pump 42 driven by an electric motor 43. The pump 42 has an inlet line 44 taking fluid from a reservoir or sump 45 in the base 1 of the machine, and its displacement or output is subject to variation in response to the pressure in a control line 46 adapted to be connected to the pressure line 41 by the valve 39 when adjusted to effect traverse of the table 3.

The direction valve 39 has an intermediate or stop position, and opposite end positions to effect reversible operation of the motor 32, and in said opposite end positions serves to direct fluid discharging from the motor 32 respectively to one or the other of two exhaust lines 47 and 48. The exhaust line 47 leads to the inlet of the orifice selection valve 40 which has three positions of adjustment to direct the exhaust fluid respectively to three orifice lines 49, 50 and 51 during forward feed operation. A plurality of independently adjustable restricted orifices 52, 53 and 54 for feed control are respectively interposed in the lines 49, 50 and 51, and discharge to a drain line 56 returning to the reservoir 45. An adjustable restricted orifice 55 is connected to receive fluid from the exhaust line 48 during rapid traverse return and also discharges to the drain line 56. The selective control orifices 52, 53, 54 and 55 are, therefore, adapted to be individually

connected in the hydraulic transmission system depending on the adjustments of the valves 39 and 40 to receive fluid discharging from the actuator 32, and to build up a back pressure which is reflected in the inlet side of the system to control the pressure in the pump control line 46, and therethrough to vary the output of the pump 42 in accordance with the fluid requirements at different times in the machine cycle.

The valves 39 and 40 and the restricted adjustable orifices 52 to 55 are incorporated in a unitary valve panel 57 mounted in the front of the machine base 1. The panel 57 consists of a rectangular block (Figs. 11 and 12) suitably supported on the base 1 at the front of the machine, and formed with cored passages connected to the respective inlet and outlet lines 37, 38, 41, 46 and 56, and other cored passages defining the lines 47 to 51. Each of the orifices is provided with an indicator dial on the front of the block 57.

The direction valve 39 comprises a horizontal bore opening crosswise through the block 57 and having a valve sleeve 58 fixed therein. The sleeve 58 is formed with longitudinally spaced sets of radial ports 59, 60, 61, 62 and 63, opening to the inner periphery, and connected respectively to the cored passages 48, 37, 41, 38 and 47. Two spaced sets of restricted ports 64 and 65 are also formed in the valve sleeve 58, and are connected in parallel through fixed orifice plugs 66 to the cored control passage 46.

A valve plunger 67 of the spool type is reciprocable in the valve sleeve 58 with a snug sliding fit, and is formed with end lands 68 and 69, and an intermediate land 70 separated by peripheral grooves 71 and 72.

The orifice selection valve 40 is generally similar in construction to the direction valve 39, and comprises a horizontal bore opening crosswise through the block 57 in parallel vertical spaced relation to the bore of the direction valve. A valve sleeve 73 is fixed in the bore, and is formed with a plurality of longitudinally spaced sets of radial ports 74, 75, 76, 77 and 78 opening to the inner periphery thereof, and connected respectively to the cored passages 49, 47, 50, 47 and 51, the passages 47 being branched. Reciprocable within the valve sleeve 73 with a snug sliding fit is a valve plunger 79 having two end lands 80 and 81 and an intermediate land 82 separated by peripheral grooves 83 and 84 for selectively blocking and connecting the valve ports in different positions of adjustment of the valve.

The direction valve 39 has three positions, namely, an intermediate stop position and opposite end positions. Normally, the valve is biased by spring pressure into the intermediate stop position. A valve stem 85 projects from one end of the valve member 67 for connection to suitable actuating means, and has a rod 86 of reduced diameter extending axially through the valve member. A nut 87 is threaded onto the free end of the rod 86 to clamp the valve member rigidly to the stem 85. The stem 85 extends through a bore 88 in a bracket 89 mounted on one end of the panel block 57, and is formed with a peripheral enlargement defining a shoulder 90 in opposed axially spaced relation to the adjacent end of the valve member 67. Slidably disposed on the valve stem 85 within the bore 88 are two flanged rings 91 and 92 urged apart by a coiled compression spring 93.

The pump 42 is substantially like that shown in an application for United States Letters Patent

by Max Mathys, Serial No. 379,211, filed February 17, 1941.

In operation, when the stem 85 is not externally actuated, the spring 93 will maintain the rings 91 and 92 in spaced relation respectively against the end of the valve member 67 and the shoulder 90 and also against the end of the valve sleeve 58 and the outer wall of the bore 88. Upon actuation of the stem 85 outwardly, the ring 92 will be moved to the left by the valve member 67 to compress the spring 93. Upon actuation of the stem 85 inwardly, the ring 91 will be moved by the shoulder 90 to compress the spring 93. Upon releasing the valve stem 85 in either instance, the spring 93 will expand to return the 15 valve member 67 to intermediate position.

The orifice selection valve 40 also has three positions, and normally the valve member 79 is biased by a compression spring 94 into the intermediate position. The means coacting with the 20 spring 94 are the same in construction as in the case of the direction valve 39 and, hence, need not be again described. It is sufficient to state that the valve member 79 has an axial stem 95 projecting from one end through a bracket 96 for 25 connection to suitable actuating means.

The direction valve 39 and the orifice selection valve 40 are shiftable into their opposite end positions respectively by solenoids SVFW and SVREV and solenoids SV1 and SV2 which 30 are mounted on the rear of the block 57 and are connected in the electrical control circuits of the machine. The solenoids SVFW and SVREV for the direction valve 39 are disposed in end alignment, and have a core 97 extending axially 35 therethrough and provided on opposite ends with suitable heads 98 for limiting the extent of movement. One end of the core 97 is pivotally connected through a clevis 99 to one end of a lever 100 in turn pivotally connected intermediate its 40 ends at 101 on the bracket 89. The other end of the lever 100 is pivotally connected through two parallel links 102 in turn pivotally connected to the flattened outer end of the valve stem 85.

When both solenoids SVFW and SVREV are 45 deenergized, the spring 93 will locate the valve member 67 in its intermediate or stop position in which the lines 37 and 38, leading to opposite sides of the motor 32, are interconnected and connected to the pressure and control lines 41 and 46, and are blocked from the exhaust lines 47 and 48, thereby adjusting the pump 42 for minimum displacement sufficient to maintain a delivery pressure.

When the solenoid SVFW alone is energized, 50 the valve member 67 is shifted out of intermediate position to the right so as to connect the pressure port 61 to the motor line 37 and to connect the other motor line 38 to the exhaust passage 47. Upon deenergization of the solenoid SVFW and energization of the solenoid SVREV, the valve member 67 is shifted from the intermediate position to the left into the opposite end position to connect the motor lines 38 and 37, respectively, to the pressure line 41 and the exhaust line 48.

The solenoids SV1 and SV2 for the orifice selection valve 40 are disposed in end alignment on the rear of the panel block 57, and over the solenoids for the direction valve 39, and have a core 103 operatively connected to the stem 95 55 in the same manner as in the case of the valve 39. Upon energization of the solenoid SV1, the valve member 79 is shifted out of intermediate position to the right so as to connect the exhaust passage 47 to the passage 51 for rough 70

grinding. When the solenoid SV2 is energized, the valve member 79 is shifted into the other end position to connect the exhaust passage 47 to the orifice line 49 for finish grinding. When both solenoids are deenergized, the valve member 79 is biased into the neutral position in which it connects the exhaust passage 47 to the orifice line 50 for grinding the incomplete end thread convolution. Thus, by appropriate individual settings of the orifices 52 to 55, the speed of the motor 32 can be automatically varied as desired to translate the work table 3, for example at a slow feeding speed during each roughing pass, a faster feeding speed during each finishing pass, a speed slower than that for rough grinding during the grinding of the incomplete end thread convolution, and a high rapid traverse speed during each free return stroke.

Tool head

The tool head 6 comprises a wheel slide 104 which is mounted directly on the rearward base extension 4 for reciprocation along the ways 5 transversely of the work axis. The grinding wheel spindle 7 is suitably supported on the forward end of the slide 104 for angular adjustment in accordance with the lead angle of the thread, and is adapted to be driven through a belt 106 by an electric motor 107.

When an incomplete end thread convolution is to be removed from the leading end of the workpiece W, a second grinding wheel G' is fixed on the spindle 7 in axially spaced relation to the grinding wheel G to take a grinding cut on the convolution at the end of each roughing pass and each finish pass. The method of removing the incomplete thread convolution is more fully disclosed in a copending application for United States Letters Patent by Gilbert Stewart, Serial No. 426,112, filed January 9, 1942, to which reference may be had for a more detailed understanding. During the end portion of each grinding pass, the solenoids SV1 and SV2 are both energized to reduce the speed of the table 3.

Slidably mounted on the rear end portion of the wheel slide 104 on transverse ways 108 is a dresser slide 109 (see Fig. 8). A suitable dressing device 110 having one or more dressing tools 111 is mounted on the slide 109 and is adapted to be reversibly driven in any position of the slide by an electric motor 112 through a flexible shaft 113 to traverse the tools across the cutting contour of the wheel G.

The wheel slide 104 is adapted to be translated hydraulically either forwardly into an operative grinding position for each grinding pass, or rearwardly into an idle or dressing position for each return stroke of the table 3. The means for this purpose includes a lead screw 114 which is rotatably anchored against relative endwise movement in the lower portion of the wheel slide 104, and which is normally non-rotatable but operated as hereinafter described to impart a compensating forward feed to the slide for each dresser feed. The forward end of the lead screw 114 is in threaded engagement with a nut 115 fixed in the rear end of a cylindrical plunger or stop member 116 slidably disposed for independent longitudinal adjustment in a bore 117 in the wheel slide 104, and constrained against rotation therein by a spline key 118. A stop bolt 119 is adjustably threaded into the forward end of the stop plunger 116, and is arranged for abutting engagement with the rear end of a coacting stop plunger or member 120. A coiled tension

spring 121 is anchored at one end to the base extension 4 and at the other end to the wheel slide 104, and serves to maintain the stop bolt 119 constantly in end abutment with the stop member 120.

The stop member 120 is slidably disposed in a sleeve bearing 122 on the base extension 4, and is held therein against rotation by means of a spline key 123. Fixed in the forward end of the stop member 120 is a feed nut 124 in threaded engagement with the cross feed screw 125. The forward end of the feed screw 125 has a shaft 126 which is connected to the cross feed mechanism 12, and which constitutes an anchor adjustable individually or conjointly by the retract mechanism 13 and the taper mechanism 14 to control the position of the wheel slide 104 independently of the cross feed.

The retract mechanism 13 and the taper mechanism 14 jointly control the axial position of the cross feed screw 125 through the medium of a lever 127. One end of the lever 127 is formed with a yoke 128 engaging trunnions 129 on an end thrust bearing 130 rotatably secured on the feed screw 125. The other end of the lever 127 is similarly formed with a yoke 131 engaging trunnions 132 on an end thrust bearing 133 rotatably secured to one end of a slidable plunger 134 forming part of the taper mechanism 14. The trunnions 132 constitute a fulcrum about which the lever 127 is oscillated by the retract mechanism 13 to shift the cross feed screw 125 axially in forward and reverse directions. In its preferred form, the retract mechanism 13 includes a hydraulic actuator 135 comprising a cylinder 136 fixed in the base 1, and a piston 137 reciprocable in the cylinder and having a rod 138 pivotally connected at 139 to the lever 127 intermediate its ends. The cylinder has two fluid lines 140 and 141 adapted to be connected by a direction valve 142 reversibly to the pressure line 30 and exhaust line 31. The valve 142 is of the two-position type, and is normally biased into one end position to direct fluid into the line 141 so as to effect movement of the wheel slide 104 forwardly into its operative grinding position. A solenoid SVR is operable upon being energized to shift the valve 142 into its other end position to direct fluid into the line 140 so as to retract the wheel slide 104 into its idle or dressing position. The solenoid SVR is connected in the electric circuits for the machine, and is energized, as an incident to each reversal of the work table 3, during each return stroke, and deenergized during each grinding pass. Preferably, a throttle orifice 140a is inserted in the line 140 to control the speed of the actuator 135.

The taper mechanism 14 comprises a sine bar 143 which is mounted for angular adjustment about a pivot 144 at one end on the front of the work table 3. The other end of the bar 143 is guided by a pin and slot connection 145, and is adapted to be secured in different positions of adjustment by means of a locating clamp block 146. A vertical follower pin 147 is reciprocable in a boss 148 on a housing 149 secured to the front of a mounting plate 150 bolted to the front wall of the base 1. The upper end of the pin 147 is arranged for wiping engagement with the lower edge of the sine bar 143 in the course of the table translation. The lower end of the pin 147 engages one side of a bell crank or segment 151 pivotally mounted on a shaft 152 within the housing 149. The plunger 134 extends slidably through a bushing 153 into the housing 149,

and is formed in its inner end with a longitudinal diametrical slot 154 receiving the segment 151 which engages the outer end of the slot to complete the operative connection between the plunger 134 and the pin 147.

Upon movement of the pin 147 along the sine bar 143, the operation of the plunger 134 will be determined by the angle of the bar. If the bar is horizontal, no taper movement will result. If the bar is inclined, the plunger 134 will be shifted in the course of the table movement as determined by the angle of adjustment to oscillate the lever 127 about the fulcrum 139, and thereby adjust the grinding wheel G transversely of the work axis in accordance with the desired work taper.

Means is provided for disabling the taper mechanism 14, and in the present instance this means comprises a slide 155 mounted in the housing 149 for adjustment longitudinally of the plunger 134, and having a stop lug 156 projecting into the lower opening of the slot 154. An adjusting screw 157 extends rotatably through the front wall of the housing 149 into threaded engagement with the slide 155, and upon adjustment serves to change the position of the lug 156 and the permissible range of movement of the plunger 134. If the slide 155 is adjusted into its outermost position (Fig. 6), it serves to hold the plunger 134 in idle position out of functional association with the sine bar 143 and hence disables the taper mechanism. In this event, the trunnions 132 constitute a fixed instead of shiftable fulcrum about which the lever 127 is adapted for oscillation by the retract mechanism 13.

Grinding wheel dressing

Prior to each dressing operation, an incremental dresser feed is imparted to the dresser slide 109 to shift the dressing tools 111 toward the periphery of the grinding wheel G, and substantially at the end of each feed increment, a limit switch LS5 is actuated to institute operation of the dressing device 110. Thereupon, the dressing device 110 is operated through a cycle of forward and return dressing strokes under the control of two limit switches LSDF and LSDR.

The dresser feed mechanism includes a feed screw 158 rotatably anchored against endwise movement in the wheel slide 104 and extending into threaded engagement with a non-rotatable feed nut 159 carried by the dresser slide 109. A gear 160 is fixed on the dresser feed screw 158 and meshes with an elongated pinion 161 journaled in the base extension 4. A spiral gear 162 is fixed for rotation with the pinion 161, and meshes with a spiral gear 163 fixed on a cross shaft 164 extending through a sleeve 165 to one side of the base extension 4. The shaft 164 is journaled at opposite ends in the sleeve 165, and extends therefrom through a housing 166. A suitable hand wheel 167 is secured to the outer end of the shaft 164 and affords means for effecting manual operation of the dresser feed.

The housing 166 encloses suitable drive means for automatically operating the dresser feed shaft 164. In the present instance, the drive means comprises a ratchet 168 keyed to the shaft 164, and a gravity pawl 169 adapted for engagement with the ratchet and mounted on the end of a pawl carrier or arm 170 oscillatory about the shaft. The free end of the pawl carrier 170 is formed with a gear segment 171 operable by a hydraulic actuator 172 on the housing 166. In the present instance, the actuator comprises a

plunger 173 reciprocable in a cylinder 174 and formed in one side intermediate its ends with a longitudinal gear rack 171* meshing with the segment 171. Thus, movement of the plunger 173 in one direction will advance the pawl 169 in a feed stroke to impart rotation to the ratchet 168, and movement of the plunger in the reverse direction will oscillate the pawl in an idle return stroke.

The cylinder 174 of the hydraulic actuator 172 has two fluid supply lines 175 and 176 opening thereto at opposite ends of the plunger 173, and adapted to be connected by a direction valve 177 reversibly to the pressure line 30 and exhaust line 31. The valve 177 is of the two-position type, and is normally biased into one end position to direct fluid into the line 175 so as to effect oscillation of the pawl 169 in its free return stroke. A solenoid SVD is operable upon being energized to shift the valve 177 into its other end position to direct fluid into the line 176 so as to oscillate the pawl 169 through its feeding stroke. The solenoid SVD is connected in the electric circuits for the machine, and is adapted to be energized at predetermined points in the machine cycle, for example after every two grinding passes under the control of an electric counter having an operating coil or relay B and a clutch coil or relay A.

The extent of the dresser feed movement is adjustably controlled by a cam 178 arranged to lift the pawl 169 out of engagement with the ratchet 168 to terminate the feed. Substantially at the end of the dresser feed, the carrier 170 actuates a limit switch LS5 to initiate the cyclic operation of the dressing mechanism 15.

Upon each dresser feed, a cross feed increment of the same extent is imparted simultaneously to the wheel slide 104 so as to compensate for the reduction in the diameter of the grinding wheel G resulting from the removal of stock in the dressing operation. The compensatory cross feed drive comprises a gear 179 on the dresser feed screw 158, an idler gear 180 meshing with the gear 179, and a gear 181 on the compensatory feed screw 114 and meshing with the gear 180. It will be seen that upon rotation of the dresser feed screw 158, rotation will be imparted to the compensation cross feed screw 114 so as to retract the rear stop member 116, and thereby cause the spring 121 to advance the grinding wheel G through a like distance towards the work axis.

Cross feed mechanism

The cross feed mechanism 12 for the grinding wheel G is operable to adjust the position of the forward stop member 120 by rotating the cross feed screw 125, and thereby to control the size setting of the grinding wheel G in relation to the workpiece W. The mechanism is manually operable to adjust the grinding wheel G into initial setting as required by the diameter of a particular workpiece W to be ground, and during the machine cycle is automatically operable to impart a cross feed increment of predetermined depth once for each grinding pass, after the initial grinding pass, of the work head 8 until the thread is ground to final size or depth.

In its preferred form, the cross feed mechanism 12 comprises a body bracket 182 integral with the mounting plate 150, and formed with a bore 183 coaxial with the feed screw 125. A fixed bushing 184 is secured in the bore 183, and projects forwardly therefrom. Rotatably disposed in the bushing 184 is a tubular sleeve 185 which

constitutes the terminal or outlet shaft of the cross feed mechanism 12, and in which the screw shaft 126 is axially splined for joint rotary drive and independent axial movement.

The forward projecting end of the tubular shaft 185 is formed with axially spaced peripheral flanges 186 rotatably supporting a hub member 187. Preferably, a bearing sleeve 188 is fixed in the hub member 187, and engages the flanges 186 with a snug rotary fit. The forward end of the hub member 187 is formed integral with a circular plate 189 having a forwardly projecting annular flange 190. Rigidly secured in coaxial relation to the flange 190 is a hand wheel 191 provided with a suitable hand grip 192 for effecting a manual cross feed.

A disengageable speed-reduction gear drive is provided between the hand wheel 191 and the shaft 185. In its preferred form, this gear drive includes a large gear 193 bolted to the forward end of the shaft 185 in coaxial relation therewith. The gear 193 meshes with one end of an elongated axially shiftable pinion 194. The other end of the pinion 194 is slidable in and meshes with an internal gear 195 which is journaled in the inner face of the hand wheel 191, and is integral with an external gear 196. An idler gear 197 rotatably mounted on the inner face of the hand wheel 191 meshes with the gear 196. Meshing with the gear 197 is a gear 198 on a shaft 199 extending axially through the hand wheel 191, and provided on the outer end with a hand lever 200. A spring actuated detent 201 is carried by the free end of the hand lever 200, and is adapted when released to engage selectively in any one of an annular series of holes 202 provided at the front of the hand wheel 191 concentrically about the shaft 199.

The gear 194 is provided on one end with an axial pin 203 adapted for engagement in a recess 204 within the plate 189, and is provided on the other end with a hand knob 205 whereby it may be retracted axially out of meshing engagement with the large gear 193. A spring actuated detent 206 serves to hold the gear 194 releasably in either position of adjustment. When the gear 194 is disengaged from the gear 193, the hand wheel 191 can be rotated independently of the shaft 185 as required for coarse adjustment relative to a fixed reference point or pointer 240. Assuming the gear 194 to be in mesh with the gear 193, when the detent 201 is disengaged from the holes 202, the lever 200 may be manually revolved to effect a fine adjustment of the hand wheel 191 relative to the shaft 185, the gears 198, 197, 196 and 195 acting to roll the gear 194 about the gear 193. If the hand wheel 191 is held against rotation, operation of the lever 200 will rotate the gear 193 to adjust the screw 125. By these operations, the screw 125 may be adjusted into correct size position, with the wheel 191 registering with a zero point. When the detent 201 is engaged in any one of the holes 202, the hand wheel 191 is locked through the gear train to the shaft 185 for direct rotation therewith.

A pawl and ratchet mechanism is provided for imparting an incremental automatic feed adjustment to the shaft 185, and preferably comprises a ratchet 207 rigidly secured to the rear end of the hub member 187. A pawl carrier 208 is mounted for oscillation on the outer end of the bushing 184, and is confined in axial position between the plate 150 and the end of the hub member 187. Pivotedly mounted by a pin 209 in the end of the pawl carrier 208 is a pawl 210 adapted for en-

gagement with the periphery of the ratchet 207. A spring detent 211 coacts with the pin 209 to maintain the pawl 210 either in operative position to engage the ratchet 207 or in a lifted position out of engagement with the ratchet.

The carrier 208 is formed with a gear segment 212 which meshes with a pinion 213 on the forward end of the shaft 214 rotatably disposed within a bore 215 in the body bracket 182. A pinion 216 on the rear end of the shaft 214 meshes with a gear rack 217 on one side of a longitudinal rack bar 218 reciprocable in and projecting from a transverse bore 119 in the body bracket 182. The outer end of the rack bar 218 is pivotally connected at 220 through a connected rod 221 to a crank 222 operable by a hydraulic actuator 223. In the present instance, the hydraulic actuator 223 is mounted on the front of the machine base 1, and comprises a piston 224 reciprocable within a cylinder 225 and connected through a rack 226 and pinion 227 to the crank 222. The cylinder 225 has two fluid lines 228 and 229 adapted to be connected by a direction valve 230 reversibly to the pressure line 30 and exhaust line 31. The direction valve 230 is of the two-position type, and is normally biased into one end position to direct fluid into the line 228 so as to effect movement of the pawl 210 in a return stroke. A solenoid SVD is operable upon being energized to shift the valve 230 into its other end position to direct fluid into the line 229 so as to move the pawl 210 in a feeding stroke. At the end of the feeding stroke, a cam 231 on the crank 222 acts to open a limit switch LSF to interrupt the circuit for the solenoid SVD.

The amount of each cross feed increment is adjustable by varying the effective stroke of the pawl 210. The means for this purpose includes a rotary shield 232 overlying the periphery of the ratchet 207, and adapted to lift the pawl 210 out of engagement with the ratchet teeth after a predetermined extent of pawl movement. The shield 232 is rotatable about a ring 233 which encircles the hub member 187, and which is rigidly bolted to the body housing 182 to secure the cross feed mechanism 12 in mounted position. A feather 234 on the housing 182 extends through a slot 235 in the shield 232 into a groove 236 in the ring 233, and serves as an additional means for securing the parts in assembled relation. A hand knob 237 is secured to the shield 232 by means of a bolt 238 extending through a peripheral slot 239 in the ring 233, and affords means for adjusting the shield relative to the pawl 210. Encircling the ring 233 and rigidly secured thereto outwardly from the shield 232 is an annular disk 239 which interfits rotatably with the outer edge of the plate 189 and supports the pointer 240 for indicating the adjustment of the hand wheel 191.

The hand wheel 191 controls a limit switch LSSI for initiating the end of the machine cycle when the cross feed reaches final size. The switch LSSI has an arm 241 connected through a link 242 to an arm 243 on a shaft 244 journaled in the base 1. Secured to the forward end of the shaft 244 is an arm 245 in which a finger 246 is adjustably pivoted for swinging movement into or out of operative position. A fixed dog 247 is secured to the hand wheel 191, and is arranged to engage one side of the finger 246 to actuate the switch LSSI at the end of the cross feed. A second dog 248 is adjustably secured in a peripheral T-slot 249 in the wheel 191, and is adapted to be brought into engagement with the other

side of the finger 246 to set the switch LSSI at the start of the cycle. The spacing of the dog 248 from the dog 247 determines the extent of cross feed of the wheel slide 104.

Hydraulic circuits

The various operating elements of the hydraulic circuits have been described in the foregoing. It is to be noted that one portion of the circuit 10 provides a hydraulic drive for the work table 3 and spindle 10. This portion receives fluid under full pressure from the pump 42 through the line 41. A relief valve 250 is connected to the line 41 to discharge excess fluid at a given pressure through a bypass line 251 and the exhaust line 56 to the sump 45. The other portion of the circuit serves various hydraulic actuators of the machine proper, viz., the retract actuator 135, the dresser feed actuator 172 and the cross feed actuator 223, and receives fluid at a constant low pressure from the pump line 41 through a pressure reducing valve 252 to the line 30.

Electrical control circuits and operation

Current is supplied for all of the various motors, excepting the grinding wheel motor 107, from three main supply lines L₁, L₂, L₃, which are adapted to be connected to a suitable source of three-phase alternating current by a main disconnect switch S₁. Suitable lower voltage current for the control circuits proper is derived from a step-down transformer 253 having a primary winding connected across the supply lines L₁, L₃ and a secondary winding, with a line L₄ connected to one terminal and a line L₅ connected to the other terminal. A line L₆ is adapted to be connected to the lead L₅ upon closing a normally open start switch S₂ for the hydraulic motor 43. Accordingly, the various electrical control devices of the system may be energized by connecting them across either the lines L₄ and L₅ or L₄ and L₆.

The hydraulic pump motor 43 and a lubrication pump motor 254 are adapted to be connected in parallel to the lines L₁, L₂ and L₃ through a set of normally open switch contacts H² controlled by a relay H. To start the pump motors 43 and 254, the start switch S₂ is closed, thereby completing a circuit for the relay H across the lines L₄ and L₅, the circuit being from L₄ through the relay H, a series of overload and protective relays, a normally closed master stop switch S₃, and the switch S₂ to the line L₅. Energization of the relay H closes the contacts H² to set the pump motors 43 and 254 in operation, and also closes sealing contacts H' to establish a holding circuit around the starting switch S₂. When contacts H' are closed, lines L₅ and L₆ are connected to condition the circuits for connecting the cycle control devices across the lines L₄ and L₅.

Closing of the switch S₂ also establishes a circuit across the lines L₄ and L₅ for the solenoid SV1 through normally closed contacts CR31' and a normally closed limit switch LS13. A parallel circuit for the solenoid SV2 is interrupted at this time by normally open contacts CR31². The solenoid SV1 upon being energized serves to actuate the valve 40 to direct the discharge of the hydraulic motor 42 through the adjustably restricted orifice 54 set to control the table speed for rough grinding. In the event that the end thread convolution is not to be removed, the solenoid SV1 and the limit switch LS13 may be removed from the circuit.

A circuit is also established across the lines L₄ and L₅ for a relay CR1 and the solenoid SVCR through a limit switch LSTA upon movement of the table 3 to the right. The solenoid SVCR actuates the valve 28 to effect operation of the actuator 23 in a direction to provide a backlash compensation to the right. Upon reversal of the switch LSTA at the end of the table travel to the right, the circuit for the relay CR1 and the solenoid SVCR is interrupted, and a parallel circuit is established for a relay CR9 and the solenoid SVCL. As a result, the valve 28 is reversed to effect a backlash compensation to the left.

The grinding wheel motor 107 is adapted to be connected across lines L₇ and L₈ connected to a source of direct current, and comprises a series field 255, a shunt field 256, and a starter 257 having an operating coil OP with a timer (not shown). The field 256 is connected in series with two adjustable resistances 258 and 259 across the lines L₇ and L₈.

To start the wheel motor 107, and also a coolant pump motor 260 and refrigeration unit motor 261, a hand switch S₄ is closed to complete a circuit for relays C and REFR through a stop switch S₅. The relay C closes sealing contacts C' across the switch S₄, contacts C² to complete a circuit through the operating coil OP, and contacts C³ to connect the motor 260 to the lines L₁, L₂ and L₃. Upon energizing the coil OP, contacts OP³, OP² and OP⁴ of the starter 257 are closed successively to start the grinding wheel motor 107. At this time, the resistance 259 is shunted out through the contacts CR31⁴, so that the motor 107 is operating at a relatively low speed adapted for rough grinding. The coil REFR closes contacts REFR' to connect the motor 254 to the lines L₁, L₂, L₃. Consequently, closing of the switch S₄ effects operation of all three motors 107, 254 and 260.

Various selector switches are provided for conditioning the circuit to obtain a particular machine cycle. Switch S₆ is adjustable to control the cycle for either hand operation, single cut operation or automatic operation, and in the position shown closes all of its contacts to provide for automatic operation. Switch S₇ is adjustable to condition the counter for counting table strokes or workpieces, and as shown, provides for the counting of strokes, for example, four strokes including two grinding passes. Switches S₈ and S₉, in parallel and located at the front and rear of the machine, are adjustable to effect continuous wheel dressing or intermittent dressing, or to disable the dressing mechanism, and as shown, provide for intermittent dressing.

At the start of the cycle, relays CR1, CR10, CR3 and CR15, and solenoid SVR are energized, and the lamp RED is illuminated. The solenoid SVR maintains the wheel slide 104 in retracted position.

The machine cycle is started by actuating a start cycle switch S₁₀ to close a circuit across the lines L₄ and L₅ through a relay CR1, this circuit including a closed limit switch LSS1. Excitation of the relay CR1 closes sealing contacts CR1⁴ across switch S₁₀, and contacts CR1' to complete a circuit for a coolant valve solenoid 262 across lines L₁ and L₃. The circuit for the relay CR1 will remain closed unless a stop cycle switch S₁₁ or the master stop switch S₃ is opened, or until the limit switch LSS1 is opened at the end of the wheel cross feed.

The relay CR1 also opens contacts CR1² to

break the circuit for relays CR1 and CR10 and the solenoid SVR. Deenergization of the solenoid SVR causes the valve 42 to shift so as to effect advance of the grinding wheel G into operative grinding position.

Upon release of the start cycle switch S₁₀, and after a time delay, the relay CR1 causes closing of contacts CR1' to complete a circuit for relays CR4 and CR8 and solenoid SVFW. Relay CR4 closes sealing contacts CR4⁴ to establish a holding circuit. Solenoid SVFW shifts the valve 39 to effect movement of the work table 3 in a forward rough grinding pass.

The relay B of the counter and the clutch relay A are connected across the lines L₄ and L₅, and hence are in a state of energization. When the relay CR4 is energized, it opens contacts CR4³ to interrupt the circuit and register a pass on the counter. Since three passes of the preceding cycle were already registered thereon, the counter closes contacts 263 to complete a circuit for relay CR6 which closes sealing contacts CR6⁴. The relay CR6 also closes contacts CR6³ in the circuit for the dresser feed solenoid SVD, but this circuit is not completed since contacts CR4² are open.

Near the end of the first roughing pass, the table 3 opens the limit switch LS13 to deenergize the solenoid SVI, and thereby reduces the feeding speed for grinding the incomplete end thread convolution by the grinding wheel G'.

At the end of the first roughing pass, the table 3 actuates the switch LSTA to break the circuit for the relay CR1 and solenoid SVCR and to make the circuit for the relay CR9 and solenoid SVCL.

Relay CR9 closes contacts CR9³ to close again the circuit for the relay CR10 and solenoid SVR. The relay CR10 closes contacts CR10⁴ to complete the circuit for the solenoid SVD for effecting the dresser feed, and the solenoid SVR effects retraction of the grinding wheel G. The relay CR10 also closes contacts CR10⁵ to complete the circuit through contacts CR9¹ and CR9² for the solenoid SVREV and relay CR5 to effect free return movement of the table 3 to the left.

Operation of the dressing mechanism 15 continues during the wheel retract movement and the table return movement. At the conclusion of the dresser feed, the limit switch LS5 is closed momentarily to complete the circuit for dresser relay DF, which closes sealing contacts DF³ and opens interlock contacts DF'. Relay DF also closes contacts DF² to complete a circuit for relay CR32 through contacts CR6². Relay CR32 closes contacts CR32³ to shunt out the resistances 258 and 259 so as to rotate the grinding wheel motor 107 at a slow dressing speed.

The dresser 110 now operates forwardly, and closes the limit switch LSDR to prepare the circuit for relay DR. At the end of the forward dresser movement, the limit switch LSDF is opened, and upon resultant closing of contacts DF', the dresser relay DR is energized, opening interlock contacts DR⁴ and closing contacts DR⁵. The dresser now operates in the reverse direction during which the switch LSDF is closed, and at the end of which the limit switch LSDR is again opened to terminate the dresser operation.

When the contacts DR⁴ are opened at the end of the forward dressing stroke, the relay CR6 is deenergized, but the circuit for the relay CR32 is maintained by the contacts DR⁵. At the end of the dresser operation, the contacts DR⁵ open to break the circuit for the relay CR32. As a re-

sult, the motor 107 is again driven at rough grinding speed.

At the end of the return movement of the table 3, the limit switch LSTA is again actuated to break the circuit for the relays CR5 and CR8 and the solenoid SVREV, and to close the circuit for the relay CR7 and the solenoid SVCR. Opening of contacts CR9³ breaks the circuit for the relay CR10 and solenoid SVR so that the wheel slide 104 is advanced into operative grinding position.

Contacts CR8² and CR10³ now being closed, the solenoid SVF is energized to impart a cross feed increment to the wheel slide 104. At the end of the cross feed, the limit switch LSF is opened to interrupt the circuit for the relay CR2. Thereupon, contacts CR2' are closed to again complete the circuit for the relays CR4 and CR8 and the solenoid SVFW for the next stroking cycle.

If the dressing operation has not been completed when the table 3 reaches the end of its return stroke, the switch LSTA will be actuated, but the table will stop and dwell in fixed starting position, since relay CR5 will drop out contacts CR5⁴ to break the holding circuit for the solenoid SVREV, and contacts CR3² will still be open. The circuit for relay CR10 and solenoid SVR will be maintained through contacts CR8' and DR⁵ to prevent advance of the wheel slide 104 even though contacts CR9³ are now open.

At the end of the dressing operation, the contacts DR⁵ will open to interrupt the circuit for the relay CR10 and the solenoid SVR to effect a belated advance of the wheel slide 104. Closing of the contacts CR10³ will energize the solenoid SVF to impart a normal cross feed to the slide. At the end of the feed, the limit switch LSF is opened momentarily to deenergize the solenoid SVF and the relay CR2 to close contacts CR2', and start the next stroking cycle.

Energization of the relays DF and DR, respectively, serves to connect the dresser motor 112 for forward and reverse operation through contacts DF⁴ and DR' to the lines L₁, L₂ and L₃.

The foregoing cycle is repeated except that after each of the second and fourth roughing passes, the dressing operation is not instituted, and the table 3 is reversed immediately at the end of the return stroke.

At the end of the last cross feed increment, the limit switch LSS1 is actuated, but the circuit for the relay CR4 is maintained across contacts CR1³ and CR5⁵. The switch LSS1 closes the circuit for relay CR3¹ which cuts out the solenoid SV1 and connects in the solenoid SV2 to increase the table speed, and which closes the contacts CR3¹⁵ and opens the contacts CR3¹⁴ to cut out the resistance 258 and cut in the resistance 259 to increase the speed of the grinding wheel G for the last or finishing pass.

Upon reversal of the table 3 at the end of the final grinding pass, the contacts CR5⁴ are opened to interrupt the circuit for the relay CR4, but since the relay CR8 is excited, contacts CR8⁴ maintain the circuit for the coolant valve solenoid 262.

Since the relay CR4 is deenergized, the machine cycle will stop at the end of the last free return movement of the table 3.

We claim as our invention:

1. A grinding machine comprising, in combination, a base, a work table mounted on said base for translation in forward and reverse directions and supporting a rotary work spindle, a tool head supporting a rotary spindle adapted to support a grinding wheel and having a wheel slide

mounted on said base for shifting movement transversely of said table, a cross feed screw in operative association with said wheel slide and being both rotatable and axially shiftable to determine the position of said slide relative to the axis of said work spindle, a control lever extending laterally of said screw and being pivotally connected at one end to said screw, a taper mechanism mounted on said base and having a member extending parallel to said screw and being longitudinally shiftable in timed relation to the translation of said table and pivotally connected to the other end of said lever, a retract mechanism including a reversible hydraulic actuator having a piston rod extending parallel to said feed screw and pivotally connected to the intermediate portion of said lever, said taper mechanism being operable to swing said lever about the pivotal connection with said piston rod to shift said feed screw, said retract mechanism being operable to swing said lever about the pivotal connection with said member to shift said feed screw, and automatic control means operable in timed relation to the translation of said table for operating said retract mechanism to advance said slide at one end of the table movement and to retract said slide at the other end of the table movement without affecting the rotary adjustment of said feed screw.

2. A grinding machine comprising, in combination, a base, a work table mounted on said base for translation in forward and reverse directions and supporting a rotary work spindle, a tool head supporting a rotary spindle adapted to support a grinding wheel and having a slide mounted on said base for shifting movement transversely of said table, a cross feed screw in operative association with said wheel slide and being both rotatable and axially shiftable to determine the position of said slide relative to the axis of said work spindle, a control lever extending transversely of said feed screw and being pivotally connected at one end to said screw, a fulcrum for the other end of said lever, a retract mechanism including a reversible hydraulic actuator having a piston rod extending parallel to said feed screw and pivotally connected to the intermediate portion of said lever, said retract mechanism being operable to swing said lever about said fulcrum to shift said feed screw, and automatic control means operable in timed relation to the translation of said table for operating said retract mechanism to advance said slide at one end of the table movement and to retract said slide at the other end of the table movement without affecting the rotary adjustment of said feed screw.

3. A grinding machine comprising, in combination, a base, a work table mounted on said base for translation in forward and reverse directions and supporting a rotary work spindle, a tool head supporting a rotary spindle adapted to support a grinding wheel and having a slide mounted on said base for shifting movement transversely of said table either forwardly into an operative position or rearwardly into an idle or retracted position, a cross feed screw in operative association with said wheel slide and being both rotatable and axially shiftable to determine the position of said slide relative to the axis of said work spindle, a control lever extending transversely of said feed screw and being pivotally connected at one end to said screw, a taper mechanism mounted on said base and having a member extending parallel to said screw and being longitudinally shiftable

in timed relation to the translation of said table and pivotally connected to said lever, a retract mechanism including a reversible hydraulic actuator having a piston rod extending parallel to said feed screw and pivotally connected to said lever, said taper mechanism being operable to swing said lever about the pivotal connection with said piston rod to shift said feed screw, said retract mechanism being operable to swing said lever about the pivotal connection with said member to shift said feed screw, and automatic control means operable in timed relation to the translation of said table for operating said retract mechanism to advance said slide at one point in the table movement and to retract said slide at another point in the table movement.

4. A grinding machine comprising, in combination, a base, means on said base for supporting a rotary work spindle, a wheel slide mounted on said base for shifting movement either forwardly into an operative position in relation to said spindle or rearwardly into an idle or retracted position and adapted to support a rotary grinding wheel, a cross feed screw in operative association with said slide and being both rotatable and axially shiftable to determine the position of said slide relative to the axis of said work spindle, a cross feed mechanism for rotating said screw, a control lever pivotally anchored at one point to said feed screw, a fulcrum for said lever, a retract mechanism including a reversible hydraulic actuator having a piston rod extending parallel to said feed screw and pivotally connected at another point to said lever, said retract mechanism being operable to swing said lever about said fulcrum to shift said feed screw, and automatic control means for effecting reversal of said actuator to shift said screw without altering the rotary adjustment of said screw.

5. A grinding machine comprising, in combination, a base, a work table mounted on said base for translation in forward and reverse directions and supporting a rotary work spindle, a tool head supporting a rotary spindle for driving a grinding wheel and having a slide mounted on said base for shifting movement transversely of said table, a front stop member mounted in said base for sliding adjustment longitudinally of said slide and being rigid with a non-rotary feed nut, a rear stop member mounted in said slide for adjustment longitudinally of said slide and being rigid with a non-rotary compensator feed nut, spring means for maintaining said stop members in end abutting engagement, a dressing device slidably mounted on said wheel slide for movement forwardly toward said grinding wheel spindle, drive means for automatically adjusting said dressing device, drive means operable by said first mentioned drive means and including a compensating feed screw rotatably anchored in said wheel slide and engaging said compensating nut for retracting said wheel slide relative to said compensating nut in timed relation to the forward adjustment of said dressing device, a cross feed screw adjustably threaded into said feed nut, an adjustable anchor for said feed screw, a cross feed mechanism axially splined to said screw for rotating the latter to adjust the position of said forward stop member, a taper mechanism, and a retract mechanism, said taper mechanism and retract mechanism being operable singly or conjointly to shift the position of said anchor independently of said cross feed mechanism.

6. A grinding machine comprising, in combination, a base, a table mounted on said base for

translation in forward and reverse directions and supporting a rotary spindle, a head supporting a second spindle and having a slide mounted on said base for shifting movement transversely of said table, a front stop member mounted in said base for sliding adjustment longitudinally of said slide and being rigid with a non-rotary feed nut, a rear stop member mounted in said slide for adjustment longitudinally of said slide and being rigid with a non-rotary compensator feed nut, spring means for maintaining said stop members in end abutting engagement, a compensating feed screw rotatably anchored in said wheel slide and engaging said compensating nut, means for rotating said screw to shift said slide relative to said compensator nut, a cross feed screw adjustably threaded into said feed nut, an adjustable anchor for said feed screw, a cross feed mechanism axially splined to said feed screw for rotating the latter to adjust the position of said forward stop member, and means for adjusting said anchor to shift said slide independently of said cross feed mechanism.

7. A grinding machine comprising, in combination, a base, a slide mounted on said base for shifting movement, a front stop member mounted in said base for sliding adjustment longitudinally of said slide, a non-rotary feed nut fixed to said member, a rear stop member mounted in said slide for adjustment longitudinally of said slide, a non-rotary compensator feed nut fixed to said rear stop member, means for maintaining said stop members in abutting engagement, a compensator feed screw rotatably anchored in said wheel slide and adjustably threaded into said compensator nut, means for rotating said screw to shift said slide relative to said rear stop member, a rotary cross feed screw adjustably threaded into said feed nut, means for rotating said cross feed screw to shift said front stop member axially relative to said cross feed screw, an adjustable anchor determining the axial position of said cross feed screw, and means on said base for supporting said anchor and being adjustable to shift said anchor so as to shift said slide and stop members as a unit.

8. A grinding machine comprising, in combination, a base, means for supporting a rotary spindle on said base, a slide mounted on said base for shifting movement transversely of the axis of said spindle, a cross feed screw operatively associated with said slide for axial shifting movement therewith and being rotatable to effect relative feeding movement thereof, means providing an adjustable anchor for said screw, a cross feed mechanism having an outlet drive shaft axially splined to said screw to permit relative axial movement thereof and operable to rotate said screw, and a plurality of independent means operable singly and conjointly to shift said anchor independently of said cross feed mechanism.

9. A grinding machine comprising, in combination, a base, means for supporting a rotary spindle on said base, a slide mounted on said base for shifting movement transversely of the axis of said spindle, a cross feed screw operatively associated with said slide through separable abutments for axial shifting movement therewith and being rotatable to effect feeding movement thereof, resilient means for maintaining said abutments yieldably in engagement, means in said base providing an adjustable axial anchor for limiting the axially shifted position of said screw, a cross feed mechanism splined to said screw to permit relative axial movement thereof

and operable to rotate said screw, and a retract mechanism having an hydraulic actuator connected to said anchor and thereby said screw and operable to shift said anchor reversibly either into an advanced position or into a retracted position.

10. A grinding machine comprising, in combination, a base, a stop member supported in said base for sliding movement and constrained against rotation, a non-rotary screw element fixed to said member for movement therewith, a rotary screw element in threaded engagement with said non-rotary screw element, means for rotating said rotary screw element and splined thereto to permit relative axial movement, an anchor adjustably fixed in said base for determining the axial position of said rotary screw element, a slide mounted on said base for translation longitudinally of said screw elements, yieldable means for normally maintaining said slide in abutting engagement with said stop member for axial movement therewith, and means for shifting said anchor alternately through a predetermined range of movement either into an advanced position or a spaced retracted position.

11. A grinding machine comprising, in combination, a base, means on said base for supporting a rotary spindle, a slide mounted on said base for shifting movement transversely of the axis of said spindle, a stop abutment mounted in said base for adjustment transversely of said spindle, a feed screw for adjusting said abutment, a second abutment mounted on said slide for separable engagement with said first mentioned abutment, yieldable means for maintaining said abutments in follow-up engagement, cross feed means for rotating said screw, and means for controlling the axial position of said screw and being operable to shift said screw axially independently of said cross feed mechanism so as to superimpose a shifting adjustment of said slide on the cross feed adjustment of said slide.

12. A grinding machine comprising, in combination, a base, a table supporting a rotary work spindle and mounted for translation on said base axially of said spindle, means on said table for rotating said spindle and translating said table in positive timed relation, a hydraulic transmission for said last mentioned means including a variable delivery pump, a reversible hydraulic motor, a direction valve for connecting said pump reversibly to said motor, speed control means for throttling the exhaust from said motor to control the volumetric displacement of said pump, whereby to obtain one speed for rough grinding, another speed for finish grinding and a third speed for grinding an end thread convolution, a cross slide supporting a grinding wheel spindle adapted to support a grinding wheel and mounted on said base for shifting movement transversely of said work spindle, an electric motor for driving said grinding wheel spindle, a dressing device for dressing said grinding wheel, and means for varying the speed of said electric motor to drive said wheel spindle at one speed for rough grinding, another speed for finish grinding and a third speed for dressing.

13. A grinding machine comprising, in combination, a base, a table supporting a rotary work spindle and mounted for translation on said base axially of said spindle, means on said table for rotating said spindle and translating said table in positive timed relation, a hydraulic transmission for said last mentioned means including a

variable delivery pump, a reversible hydraulic motor, a direction valve for connecting said pump reversibly to said motor, speed control means for throttling the exhaust from said motor to control the volumetric displacement of said pump whereby to obtain one speed for rough grinding and another speed for finish grinding, a cross slide supporting a grinding wheel spindle and mounted on said base for shifting movement transversely of said work spindle, an electric motor for driving said grinding wheel spindle, and means for varying the speed of said electric motor to drive said wheel spindle at one speed for rough grinding and another speed for finish grinding.

14. In a grinding machine, in combination, a base, a table reciprocable on said base, a spindle rotatably mounted on said table for reciprocation therewith, drive means mounted on said table for rotating said spindle and translating said table in positive timed relation, a variable delivery pump having a pressure responsive control for varying the pump displacement, a reversible hydraulic motor, a direction valve for connecting said pump reversibly to said motor, an exhaust line including a restricted orifice for receiving fluid discharging from said motor upon movement of said table in a reverse direction to provide rapid traverse, a second exhaust line for receiving fluid discharging from said motor upon movement of said table in a forward direction, an orifice selection valve in said second exhaust line, a plurality of drain lines including individual restricted feed control orifices adapted respectively to receive the discharge fluid in different positions of said selection valve to provide different feed rates, and means automatically operable in timed relation to successive passes of said table for controlling said valves whereby to effect movement of said table at one speed for a predetermined number of passes in said forward direction and at another speed thereafter for a predetermined number of passes in said direction and at still another speed during the end portion of said passes.

15. A grinding machine comprising, in combination, a base, a table reciprocable on said base in forward and reverse directions and supporting a rotary spindle, a cross slide reciprocable on said base transversely of said table either into an advanced operative position or a retracted idle position and supporting a rotary spindle, one of said spindles being adapted to support a grinding wheel and the other spindle being adapted to support the work, adjustable means defining said operative position, means automatically operable to reciprocate said table a predetermined number of times at a first feeding speed in each forward direction and a rapid traverse speed in each reverse direction and then another time at a second feeding speed in said forward direction and said rapid traverse speed in said reverse direction, means for driving the work spindle in positive timed relation to said table, means automatically operable to locate said slide in operative position during each forward movement of said table and in retracted position during each reverse movement of said table, means for adjusting said first mentioned means to advance said operative position of said slide step-by-step in timed relation to successive reciprocations of said table, and means for automatically driving said grinding wheel spindle at one rotary speed during said predetermined number of reciprocations.

tions and then at another rotary speed during
said other reciprocation.
